Primary Examiner — Philip S Hyder(74) *Attorney, Agent, or Firm* — Salter & Michaelson(57) **CLAIM**

The ornamental design for a roller cutter, as shown and described.

DESCRIPTION

FIG. 1 is a perspective view of a roller cutter, showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevation view thereof; and,

FIG. 7 is a rear elevation view thereof.

The broken lines depict portions of the roller cutter in which the design is embodied that are not considered part of the claimed design.
